UNITED STATES PATENT OFFICE.

NATHAN COZATSKY, OF NEW HAVEN, CONNECTICUT, ASSIGNOR TO SOLAR LIGHT COMPANY, OF NEW YORK, N. Y.

DESIGN FOR A GAS-LAMP SOCKET.

51,854.

Specification for Design.

Patented Mar. 12, 1918.

Application filed December 6, 1917. Serial No. 205,904. Term of patent 3½ years.

To all whom it may concern:

Be it known that I, NATHAN COZATSKY, a citizen of the United States, residing at New Haven, in the county of New Haven and State of Connecticut, have invented a new, original, and ornamental Design for Gas-Lamp Sockets, of which the following is a specification, reference being had to the accompanying drawing, forming part thereof.

The figure is a perspective view of a gas lamp socket showing my new design.

I claim:

The ornamental design of a gas lamp socket as shown.

NATHAN COZATSKY.
